UNITED STATES PATENT OFFICE.

BRYAN J. O'NEILL, OF PEORIA, ILLINOIS.

CAR-BRAKE.

1,346,971.

Specification of Letters Patent. Patented July 20, 1920.

Application filed October 28, 1918. Serial No. 259,912.

To all whom it may concern:

Be it known that I, BRYAN J. O'NEILL, citizen of the United States, residing at Peoria, in the county of Peoria and State of Illinois, have invented certain new and useful Improvements in Car-Brakes; and I do hereby declare that the following is a full, clear, and exact description of the invention, which will enable others skilled in the art 10 to which it appertains to make and use the same.

This invention relates to car brakes, pertaining more particularly to a brake mechanism for freight cars.

15 An object of the invention is to provide for quickly setting and releasing the brake shoes with the least amount of movement of the usual brake-staff.

Another object is the provision of a simple 20 form of mechanism in a brake, including a rock arm supported at the middle of its length having an extension at each extremity engaging each side of the usual chain extending to the brake-shoe structure, the 25 tensions in the rotation of the arm on its axis quickly taking up and quickly releasing or "letting off" such chain.

To the end that my invention may be fully understood, I have provided the appended 30 drawing, in which—

Figure 1 is a plan of the end of a car showing my brake mechanism attached thereto.

Fig. 2 is a side elevation of a portion of a 35 car showing my brake device in the "off" position produced on a much larger scale.

Fig. 3 is a similar view showing the operating mechanism in another position or 40 that position for taking up the brake chain.

Fig. 4 is a sectional elevation of parts 45 shown in Fig. 2 on line $x-x$, Fig. 1; and.

Fig. 5 is a plan of the device detached 50 from the car, parts being shown in section.

1 is a casting supported on the car as by 55 bolting it to the underside of the same, for example, being provided with a bore 2 to take a shaft 3. Said casting is further provided with a pair of forwardly extending arms 4 to take the lower end of the usual 60 brake staff 5 which, though not so shown, may be operated from either the top or the side of the car in the usual manner. Upon 65 said staff is a worm 6 interposed between the described arms 4 said worm being in mesh with a worm-wheel 7 affixed to one end 70 of the described shaft 3. The other end of

the shaft carries a cross-arm 8 having a stud 9 at each end equally spaced from the axis of the shaft. The studs preferably are each provided with a sheave-wheel 10, 10', their 60 grooves serving to permit the entrance between them of the usual brake chain 11, the peripheries of the wheels lying close together for holding said chain in place.

12 is any suitable member attached to any 65 desired portion of the car for attachment thereto of one end of the chain. The opposite end of the chain extends to and is connected with the usual brake shoe mechanism (not shown). The "off" position of 70 the device is shown in Fig. 2, the sheave-wheel 10 being uppermost, the wheel 10' being lowermost. A line drawn through their axes of rotation lies substantially at an angle of inclination of about 45° , the 75 chain 11 in this position allowing the brake shoes to hang free. In setting the brake the usual turning of the brake staff 5 through the worm and worm-wheel 6 and 7 respectively, the shaft 3 is moved through substantially a quarter turn, the wheel 10' being brought to an elevated position, the wheel 10 moving to the lower position. In this movement the chain is drawn upon to move the 80 brake shoes against the car wheels. The 85 wheel 10 in turning with the shaft 3 rides down upon the fixed end of the chain while the wheel 10' acts with said wheel 10 to draw the chain to its extreme tension.

The provision of the spaced wheels 10 90 and 10' in the short travel imparted to them causes all the slack in the chain to be quickly taken up before any real brake setting takes place, after which a continued rotation of the brake staff applies the power 95 to set the brakes, the whole object, as has been intimated, being that of quickly setting or releasing the brakes with the least amount of rotation of the hand wheel, the worm and worm-wheel serving, of course, 100 to hold or lock the brake set without the use of such as the commonly used pawl and ratchet arrangement.

With my form of quick take-up and letting off of the brakes the relation of the 105 parts is such that the brake staff, by slightly more than one full rotation thereof, can accomplish the work.

By extending the chain between two portions such as the sheaves, a comparatively 110 short movement as compared with what would be required to take up the same

amount of slack upon a drum is all that is necessary from the fact that the sheaves exert what may be termed a compound action, practically doubling the chain upon itself.

- 5 5. I am fully aware that a worm and worm-wheel mechanism is old in itself to wind a member upon a drum for braking purposes. Also that a take-up device similar to parts 8, 10, 10' herein has been used for 10 purposes other than for a car-brake mechanism.

However, neither of these types of devices have been used in conjunction to operate or set brakes on a car in so far as I am aware 15 whereby the power obtained through the slow moving worm and worm-wheel can be transmitted to such take-up device for quickly absorbing the slack in a chain which is the whole object and purpose of 20 my invention, together with the ability to afterward apply the greatest strain on the chain for setting the brakes.

Taking up a chain by means of a drum operated by a worm and worm-wheel is exceedingly slow work. The saving of time in setting a brake is of the utmost importance especially when an accident is impending, together with the intense strain that may be applied to the chain made possible by the use of my type of mechanism, the combination being wholly unique in a car-brake, and most effective.

Having thus described my invention, I claim:—

- 35 1. A brake mechanism for railway cars including in its construction, in combination, an arm mounted between its ends adapted to rock and having an extension

each side of its axis of movement, a brake-chain adapted for attachment at one end 40 to the brake beam of the car, its other end lying between the said extensions of the arm and attached to a fixed portion of the car.

32. A brake mechanism for a railway car including in its construction, in combination, a shaft, a cross-arm secured thereto including a pair of laterally extending projections spaced from one another and lying at opposite sides of the axis of the shaft, a brake-chain lying between the projections, 50 secured at one end and adapted for attachment at its other end operatively to the brake beam of the car, a worm-wheel secured on the shaft to operate the cross-arm, a worm meshing with the same, and an operating shaft on which the worm is mounted.

3. In a brake mechanism for a railway car, in combination, a shaft journaled on the car, a cross-arm secured on the shaft 60 including a pair of sheaves rotatably mounted upon the arm spaced from one another at opposite sides of the axis of the shaft, a brake-chain lying between the sheaves secured at one end and adapted at 65 its other end to operatively engage the brake beam of the car, a worm-wheel secured to the shaft, and a worm in mesh with the same, and an operating shaft on which the worm is mounted.

In testimony whereof I affix my signature in presence of two witnesses.

BRYAN J. O'NEILL.
